(57) **CLAIM**

We claim the ornamental design for a multifunction measuring instrument, as shown and described.

DESCRIPTION

FIG. 1 is a front perspective view of the multifunction measuring instrument showing our new design, with one of the plurality of removable sensor amplifiers fitted to the instrument;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a rear perspective view thereof;

FIG. 9 is a front perspective view of the multifunction measuring instrument, shown with the removable sensor amplifier removed from the instrument;

FIG. 10 is a front view thereof;

FIG. 11 is a rear view thereof;

FIG. 12 is a top view thereof;

FIG. 13 is a bottom view thereof;

FIG. 14 is a left side view thereof;

FIG. 15 is a right side view thereof;

FIG. 16 is a rear perspective view thereof;

FIG. 17 is rear perspective view thereof, with a cover positioned over a sensor amplifier receiving dock;

FIG. 18 is a front perspective view of a removable sensor amplifier receivable in the instrument sensor dock;

FIG. 19 is a front view thereof;

FIG. 20 is a rear view thereof;

FIG. 21 is a top view thereof;

FIG. 22 is a bottom view thereof;

FIG. 23 is a left side view thereof;

FIG. 24 is a right side view thereof;

FIG. 25 is a rear perspective view thereof;

FIG. 26 is a front perspective view illustrating the mounting of one of the removable sensor amplifiers with the multifunction measuring instrument; and,

FIG. 27 is a rear perspective view thereof.
